UNITED STATES PATENT OFFICE

MARCEL BERNARD, OF PARIS, FRANCE, ASSIGNOR TO SOCIETE FRANCAISE RADIO-ELECTRIQUE, OF PARIS, FRANCE, A CORPORATION OF FRANCE

LOUD SPEAKER AND LIKE APPARATUS

Application filed July 30, 1931, Serial No. 553,958, and in France August 14, 1930.

The present invention relates to improvements in loud speakers and like apparatus and has for its object to provide a sound-reproducing and sound-receiving device having a uniform response to applied vibratory energy over as wide a range of acoustic frequencies as possible.

With this object in view it is proposed in accordance with the present invention to employ as the vibratory element a plurality of conical surfaces elastically connected together and driven by means of one or more coils immersed in one or more circular air gaps of a magnetic circuit and traversed by alternating currents corresponding to the sound vibrations to be reproduced or picked up.

An essential characteristic of the invention resides in the fact that the coaxial conical surfaces which form the vibratory system of the apparatus are interconnected by elastic connecting means which in the case of at least one of the conical surfaces is attached to said surface on a circle which is intermediate the inner and outer peripheries thereof.

The invention will be better understood by reference to the accompanying drawing which represents, by way of example only, two particular methods of carrying out the invention.

Fig. 1 is a diagrammatical section of a loud speaker embodying the first form of the invention.

Fig. 2 is a side section of such a loud speaker embodying the second form.

Fig. 3 is a plan view of the suspension member to which the diaphragms and moving coils of the loud speakers may be attached.

In the views, the same reference indicia refer to the same or corresponding parts.

In the embodiment shown in Figure 1 a magnetic circuit having concentric poles N Q is provided with two annular air-gaps 1¹, 1² which are likewise concentric. In the said air-gaps are disposed cylindrical coils b₁ and b₂ which are rigidly secured to truncated conical membranes c₁ and c₂ respectively. The rigid assembly comprising the cone c₁ and its associated coil b₁ is suspended in suitable manner by means of a flexible connection from the cone c₂ and the rigid assembly comprising the

said cone c₂ and coil b₂ is suspended in a similar manner from the main structure or framework of the apparatus (not shown). The rigid elements together with their suspensions are designed more favorably to respond to different frequency bands of vibrations which as far as possible, succeed one another without any interruption of continuity in the frequency scale.

In the embodiment illustrated in Figure 2 a single circular air-gap is provided between concentric pole-pieces N, Q. A movable coil B is immersed in this air-gap and is supported in the usual manner upon a hollow tubular member 4 and this in turn is rigidly secured to a truncated conical membrane C₁. A second truncated conical membrane c₂ concentric with the first, is connected by a flexible suspension means S¹ at 7 on an intermediate circle to the cone c¹, and at its outer periphery provided with a flexible suspension means S² which is preferably clamped between or secured to a pair of ring members 9 and 10 which thus form a suspension or support for said cone. These ring members may be secured together and spaced from another ring member 11 by several tie rods or bolts 8, 8, while a hollow magnet 6 may in turn be fastened to ring member 11 of the frame thus formed. The same conditions relating to the frequency response favored by each diaphragm referred to in the description of Figure 1 are also applicable in the present case.

Figure 3 shows, by way of example only, a suspension device P which may advantageously be employed in connection with the particular embodiment illustrated in Figure 2. In this case the moving coil B which in Fig. 2 is shown supported on the hollow tubular member 4 is attached by the same to the central circular part a. The suspension of the coil B and consequently that of the cone c₁ which is rigidly attached thereto is of course effected at S₁ on the circle 7, as already indicated, on the surface of the truncated cone c₂ intermediate the ends thereof and also at the small ends of the two truncated cones by the tabs X (Figure 3). An annulus b (also shown on Figure 3) supports the small end of the truncated cone C₂ and is held by the tabs O. As

will be obvious upon inspection of Fig. 2, magnet 6 represents the magnetic circuit, the central pole piece N having an energizing field coil 5. The suspension member P may be bolted or otherwise secured in spaced manner to the pole end Q of magnet 6, if desired, by bolts or screws such as 1, 3, the presence of the latter affording adjustment of the inner ends of both cones by adjustment of the suspension member P.

By suitably proportioning and otherwise providing adjustment of the suspension members X connecting the two cones or diaphragms it will be seen that the large cone c_2 15 can be made to respond only to the low frequencies and to remain substantially unaffected by high frequencies of small amplitude. Such an arrangement results in the production of a loud speaker or electro-dynamic 20 microphone having two ranges of response and as compared with known apparatus having but one conical membrane or diaphragm as at present in common use constitutes an important improvement.

It is to be understood that the invention is capable of numerous modifications other than those described and illustrated by way of example.

Having now fully described my invention, 30 I claim:

1. An acoustic apparatus comprising a support, a moving coil, means for producing an electro-dynamic action upon said coil, a plurality of truncated conical membranes located 35 within the said support, said membranes having different dimensions, one of said membranes being partly coextensive with and spaced within the other and associated with the said coil, elastic suspension means upon 40 each of said membranes connected to another element of said apparatus and elastic suspension means connecting one of said membranes to the other.

2. An acoustic apparatus comprising a support, a moving coil, means for producing an electro-dynamic action upon said coil, a plurality of truncated conical membranes located 45 within the said support, said membranes having different dimensions and facing in the same direction, one of said membranes being partly coextensive with and spaced within the other and associated with the said coil, elastic suspension means upon each of said 50 membranes connected to another element of said apparatus and elastic suspension means connecting one of said membranes to another.

3. An acoustic apparatus comprising a support, a moving coil, means for producing an electro-dynamic action upon said coil, a plurality of truncated conical membranes located 60 within the said support, said membranes having different dimensions, one of said membranes being partly coextensive with and spaced within the other and associated with the said coil and an elastic connection between 65

the edge of a smaller to a circle on the surface of the truncated cone of a larger membrane and intermediate the ends thereof, elastic suspension means on each of said membranes connected to another element of said apparatus.

4. An acoustic apparatus comprising a support, a moving coil, means for producing an electro-dynamic action upon said coil, a plurality of truncated conical membranes located 70 within the said support, said membranes having different dimensions and being partly coextensive and spaced apart, one of said membranes being associated with the said coil, elastic suspension means connecting one of said membranes to another, elastic suspension means connecting the large end of the largest membrane to the support, and elastic suspension means connecting the small ends of the truncated conical membranes to the support, 80 said small ends of said latter members terminating in practically the same plane.

5. An acoustic apparatus including the combination, with a support, a movable coil, 90 means for producing an electro-dynamic action of said coil, of a plurality of truncated conical membranes disposed in spaced relation and having different dimensions, one of said membranes being partly coextensive with another and associated with the said movable 95 coil, elastic suspension means connecting the larger periphery of said one or small membrane to a larger membrane, elastic suspension means connecting the larger periphery of said larger membrane with the support, and a suspension member cut from a sheet of elastic material interconnecting said support and the smaller ends of the membranes.
